UNITED STATES PATENT OFFICE.

THOMAS S. PERKINS, OF WILKINSBURG, PENNSYLVANIA, ASSIGNOR TO WESTINGHOUSE ELECTRIC & MANUFACTURING COMPANY, A CORPORATION OF PENNSYLVANIA.

CIRCUIT-BREAKER.

1,116,475.

Specification of Letters Patent.

Patented Nov. 10, 1914.

Application filed June 12, 1905. Serial No. 264,856.

To all whom it may concern:

Be it known that I, THOMAS S. PERKINS, a citizen of the United States, and a resident of Wilkinsburg, in the county of Allegheny and State of Pennsylvania, have invented a new and useful Improvement in Circuit-Breakers, of which the following is a specification.

My invention relates to circuit-interrupting devices and has special reference to automatic overload circuit-breakers which are adapted for use with electric railway vehicle equipments.

The object of my invention is to provide a circuit-breaker that may be easily adjusted; that shall be simple and inexpensive in construction, and that shall maintain good contact between its separable terminals under adverse conditions.

Automatic car circuit-breakers of the kind most generally employed in the prior art were provided with contact brushes composed of copper strips riveted together, and these brushes were rigidly supported by a brush-holder that was attached to an operating handle. This design was deficient in that slight variations in the adjustment of the holding latch or any bur or foreign substance under any part of the contact brush materially affected the contact between the brush and the stationary contact terminal.

My invention compensates automatically for the wearing of the latch mechanism or the brush contact in a circuit-breaker, minimizes the usual deprecative effect of foreign substances under the contact brush and maintains a good contact throughout the life of the breaker. These results are accomplished by providing a movable contact brush of special construction, which comprises a plurality of contact strips clamped together and separated by spacing conductors, which do not extend to the contact end of the brush, and by a yielding connection between the brush holder and the operating handle.

My invention is illustrated in the accompanying drawings, in which—

Figure 1 is an elevation and Fig. 2 a plan view of an automatic car circuit-breaker constructed in accordance therewith, the casing being shown in section in each of said figures, and Fig. 3 is a partial elevation in which the catch mechanism of the breaker of Figs. 1 and 2 is more fully disclosed.

Referring to the drawings, a tripping lever 1 may be actuated in opposition to a spring 2 either automatically, by an overload tripping coil 3, or manually, by a tripping plunger 4, to strike one end of a catch 5, which comprises a lever arm 6 that is pivotally supported near its middle point and is provided with a projection 7 near one end, which is held in engagement with a corresponding projection 8 on a portion of an operating handle lever 9 by a spring 10. When the tripping lever strikes the catch 5, the handle lever is released and is actuated to open the circuit by a spring 11.

When the breaker is closed, the circuit is completed by a contact device 12, which comprises an arc-breaking contact member 13 and a current-carrying contact member 14, both of which are pressed against a contact block 15, the arc-breaking contact member 13 being arranged to make contact before and to break contact after the member 14, in a manner well known in the art.

The current-carrying contact member 14 is composed of a plurality of flexible metal strips 16 and a plurality of relatively short metal spacing strips 17 bolted together and to an arm or support 18. The free portions of the strips 16 are of different lengths and have beveled contact ends located in a plane that makes an angle of less than ninety degrees with the strips themselves, and the free ends of the spacing strips 17 occupy a plane that is substantially parallel to the plane of the beveled ends of the strips 16. By reason of this construction, the strips 16 are flexible to substantially the same degree and if any of the strips 16 are held away from the contact strip 15 by a bur or some foreign substance, good contact between the other strips and the terminal 15 may still be maintained.

The arm 18, which supports the contact members 13 and 14, is mounted upon a pin 19, about which it and its operating handle 9 may rotate, the relative motion of the two being limited by a pin 20 which fits loosely in a hole 21 in a projection 22 of the handle 9 and in a hole 23 in a projection 24 of the arm 18, and is prevented from slipping out of said parts by cotter-pins 25 located near its extremities and outside the projections 22 and 24. A spring 26 surrounds the pin 20, between the projections 22 and 24, and tends to force said projec-

tions away from each other and to press the beveled ends of the strips 16 against the contact block 15 when the operating handle is held in its closed position by the 5 catch 5. The arc-breaking contact member 13 is movably attached to the arm 18 by a pin 27 and is held slightly in advance of the beveled ends of the strips 16 by a spring 28 which acts against a projection 29 on 10 said arm.

The spring connections between the operating handle and the arm 18 and between the arc-breaking contact member and said arm insure a good contact between the stationary and the movable contact members without necessitating a very close adjustment of the operating handle 9 or the catch 5 and also take up any wear that may occur at the point of contact or in the catch 20 mechanism. The spring connections here shown and described are not essential to my invention, as any other convenient, yielding connection may be employed between the two parts. I desire it to be also understood 25 that my invention is not limited to any specific type of circuit-breaker or to any specific service.

I claim as my invention:

1. The combination of a stationary contact member and a movable contact member one of which comprises a plurality of contact strips of different lengths, and a plurality of relatively short interpolated spacing conductors the free ends of which 30 35 occupy a plane substantially parallel to that of the free ends of the contact strips.

2. The combination of a stationary contact member and a movable contact member one of which comprises a plurality of contact strips rigidly clamped together and 40 having beveled free ends, and a plurality of relatively short interpolated spacing conductors of different lengths the free ends of which occupy a plane substantially parallel to that of the beveled free ends of the contact strips. 45

3. In combination, a contact member comprising a group of laminae and a support therefor, said laminae extending outwardly different distances from the support and 50 having equal effective lever arms.

4. In combination, a contact member comprising a group of laminae and a support therefor, said laminae having equal effective lever arms and having at their ends contact 55 faces which are located successively different distances from the support.

5. In combination, a contact member comprising a group of laminae, spacing members between the laminae, a support for the contact member, said laminae extending outwardly different distances from said support, said spacing members being of different lengths so as to provide equal free effective lever arms for said laminae. 60 65

In testimony whereof, I have hereunto subscribed my name this 9th day of June, 1905.

THOMAS S. PERKINS.
